UNITED STATES PATENT OFFICE.

WILLIAM J. TAYLOR, OF CHESTER, ASSIGNOR TO THE TAYLOR GAS PRODUCER COMPANY, OF CAMDEN, NEW JERSEY.

GAS-PRODUCER.

SPECIFICATION forming part of Letters Patent No. 399,799, dated March 19, 1889.

Application filed May 2, 1887. Renewed October 12, 1888. Serial No. 287,975. (No model.)

To all whom it may concern:

Be it known that I, WILLIAM J. TAYLOR, of Chester, in the county of Morris and State of New Jersey, have invented certain new and 5 useful Improvements in Gas-Producers, of which the following is a specification.

The object of my present invention is to provide apparatus for gasifying fuel for making heating and other gas, or converting solid 10 fuel into gaseous fuel, with a sectional bottom composed of a series of frustums of cones suitably arranged, so that air or steam and air under pressure may be introduced directly into the interior of the bottom and distributed 15 radially, or nearly so, into contact with the fuel for effecting combustion, and thereby preventing the formation of arches of clinker and sticking or clinkering of non-combustible material to the wall of the combustion-chamber. The bottom is revolved intermittently or continuously by mechanical means for effectually grinding up clinker accumulating, and discharging it, together with ashes, 20 over the periphery of the bottom into a sealed chamber beneath while the apparatus is in full 25 operation making gas, and without interference therewith.

The nature of my invention will be fully understood, taken in connection with the accompanying drawings, forming part hereof, 30 and in which—

Figure 1 is a vertical central section through a metallic water-cooled gas-producer, showing my improved bottom with its actuating 35 devices in application. Figs. 2 and 3 are respectively transverse sections of a water-cooled gas-producer of my improved construction, taken on the lines xx and yy of Fig. 1; and Fig. 4 is a vertical central section of the 40 lower portion of my improved water-cooled gas-producer, on an enlarged scale, showing the bottom and mechanism for actuating the same.

Referring to the drawings, A is the metallic shell or casing supporting a flanged top 45 plate, B, arranged so that a supply of water may be maintained thereon for cooling off the upper portion of the producer.

C is the gas-exit pipe, fitting snugly onto 50 an annular rim, b, cast with the flanged top plate, B. D is a bosh-shaped feed-hopper, fit-

ting into a tapering annular rim, d, cast with the top plate. This hopper is provided with a bell, d' , for closing the same after fuel has been supplied to the combustion-chamber E 55 and to prevent the escape of gas therethrough. This bell d' fits snugly up against the throat of the hopper and may be operated in any suitable manner.

In the annular flanged top plate, B, is provided one or more sight-openings, F, with covers f , and which covers may be readily removed for ascertaining the condition of the fuel or for examining the interior of the producer for whatever purpose it may become 65 necessary.

E is a cylindrical metallic combustion-chamber open at the top, and preferably made of plate or boiler iron in sections riveted together. The combustion-chamber E and main 70 metallic casing A are riveted to a ring, e, supported on a flanged plate, B', which is mounted upon the sealed ash-pit H.

F' is a space between the main casing A and the combustion-chamber E for containing water admitted through a pipe, f' , provided with a stop-cock, f^2 , and which pipe is located near the bottom of the main casing A and the water or steam and water discharged from the water-jacket near the top 80 of the shell A through an overflow-pipe, f^3 , suitably supported by a strengthening-plate, f^4 , to the main casing, but, however, below the top of the combustion-chamber E.

G is a series of tubes or peep-holes arranged at suitable distances apart around the wall of and extending through the main casing A, water-jacket F', and shell E of the combustion-chamber. These peep-holes G are provided with caps g , which may be readily 90 removed for ascertaining the condition of the fuel, or the dividing-line between the ash and fuel, in the combustion-chamber.

I is a sectional bottom composed of a series of hollow frustums of cones forming hoods, 95 bolted or attached to each other in such manner that when the respective frustums—preferably decreasing in diameter from base to apex—are in position, spaces will be formed between the frustums bolted to adjoining 100 ones of less diameter, for the free passage of air or steam and air under pressure intro-

- duced directly by means of a pipe, J, into the interior of the bottom, and discharged radially, or nearly so, into contact with the fuel in the chamber E, for effecting combustion of the fuel and obviating the too free travel of the air or steam and air next the wall of the combustion-chamber, and the formation of arches of clinker and sticking of non-combustible matter to the wall of said chamber.
- 10 This characteristic feature of the producer renders it entirely practical to use anthracite coal and anthracite culm for generating the heating and other gases. It will also be observed that such construction of a producer
- 15 possesses the requisites and essential conditions for perfect combustion and for readily and effectively removing, continuously or intermittently, the non-combustible material while in full operation.
- 20 The bottom I, made of cast-iron or other suitable metal, consists of a circular base-plate, i, having cast therewith a sleeve, i', which fits around the main conduction-pipe J, extending vertically upward through the
- 25 base of the sealed ash-pit H. Around the lower portion of the conduction-pipe J is fitted a collar, i², secured rigidly thereto by means of a set-screw, i³, and against the top of this collar rests the sleeve i', which is supported thereby.
- 30 The circular base-plate i is attached to the hollow frustum I by means of stay-bolts i⁴, and this hollow frustum has preferably cast therewith a circular plate, i⁵, with, preferably, a rim, i⁶, around the periphery for forming a channel of sufficient depth for containing a supply of water for cooling off the ashes or clinker.
- 35 On the underside of the circular bottom i⁵ is provided a rack, and meshing therewith is a cog-wheel, j, supported on a shaft, j', journaled to a standard, j³, attached to the base of the sealed ash-pit H, and oppositely in the wall of the ash-pit H. Around the shaft j', close to the re-enforce plate j⁴, forming additional bearing-surface for the shaft, is fitted a collar, j⁵, with a set-screw, j⁶, for holding it to place on the shaft, and for preventing the shaft from being drawn out of its bearing in the standard j³ when operated by the crank 40 j⁷, secured thereto and provided with a handle, j⁸.
- 45 To the hollow frustum I is attached a hollow frustum, I', (smaller in diameter than the frustum I,) by means of stay-bolts h, provided with sleeves h', for holding the two frustums the proper distance apart while at the same time solidly together, and with a space between the two frustums formed for the free passage of the air or steam and air
- 50 from the interior thereof into the combustion-chamber of the producer. To the hollow frustum I' is attached in a similar manner another frustum, I², with a space between the two for the passage of the air or steam and air therefrom, and to the hollow frustum I² is similarly attached a conical-shaped hood,

I³, with a space between for permitting the air or steam and air to escape from the interior thereof into the combustion-chamber. Of course it will be observed that any desired 70 number of frustums may be used in the construction of a bottom of the character described, and hence I do not wish to limit myself to the use of the number shown in Figs. 1 and 4. Around the upper exterior surface of 75 the hollow frustum I, at suitable distances apart, and preferably cast therewith, are projecting pyramidal points j⁹, serving to grind up clinker that may accumulate in the combustion-chamber.

80 The bottom I should be diametrically so proportioned to the throat of the combustion-chamber and at such distance therefrom that the superimposed mass in the combustion-chamber will be supported so that by the mere turning of the crank the ashes or other non-combustible matter will be discharged therefrom into the ash-pit beneath, while the producer is regularly making gas and without interference therewith.

85 It will be obvious to those skilled in the art to which my invention appertains that the revolving bottom I and the upper and lower portions of the producer, with but slight modifications, may be adapted for use advantageously in a producer having brick-lined walls; and, again, by more thoroughly water-cooling the bottom by suitable means for protection when the producer is run in the reverse way, that my invention is susceptible of being used for making what is known as "water-gas" for illuminating and other similar purposes.

90 Having thus described the nature and objects of my invention, what I claim as new, and desire to secure by Letters Patent, is—

1. The combination of a bottom composed of two or more frustums of cones, sleeves between the frustums, bolts inserted through the sleeves and frustums, a plate having a depending sleeve connected with the lower frustum, a blast-pipe on which said bottom is mounted, and means, as described, for rotating said bottom, substantially as and for the purposes set forth.

115 2. The combination of a bottom composed of two or more frustums and a hood, sleeves and bolts between said frustums and hood, a base-plate attached to the lower frustum, a blast-pipe extending upward into said bottom, a collar adjustable on said pipe, and mechanism, as described, for rotating said bottom, substantially as and for the purposes set forth.

120 3. In a gas-producer, the combination of a bottom consisting of two or more hollow frustums of cones and a hood, bolts inserted through sleeves between the frustums and hood, a base-plate secured to the lower frustum with a sleeve, a blast-pipe extending upward through said sleeve, and a collar secured to said pipe, all arranged for support-

ing fuel and permitting of the admission of the air or steam and air directly into the combustion-chamber, and means, as described, for rotating said bottom, and thereby permitting 5 of the discharge of accumulating non-combustible material over the periphery of the bottom while the producer is in operation.

In witness whereof I have hereunto set my hand in the presence of two subscribing witnesses.

WM. J. TAYLOR.

Witnesses:

HERMANN BORMANN,
THOMAS M. SMITH.
